UNITED STATES PATENT OFFICE.

WILLIAM P. BETTENDORF, DECEASED, LATE OF DAVENPORT, IOWA, BY JOSEPH W. BETTENDORF, ADMINISTRATOR, OF DAVENPORT, IOWA.

DRAFT-RIGGING.

1,223,755.

Specification of Letters Patent. Patented Apr. 24, 1917.

Original application filed March 13, 1907, Serial No. 362,176. Divided and this application filed July 22, 1915, Serial No. 41,262. Renewed March 19, 1917. Serial No. 155,948.

To all whom it may concern:

Be it known that I, JOSEPH W. BETTENDORF, administrator of the estate of WILLIAM P. BETTENDORF, deceased, hereby declare that 5 said WILLIAM P. BETTENDORF was a citizen of the United States of America, and a resident of Davenport, county of Scott, and State of Iowa, and was the inventor of certain new and useful Improvements in Draft- 10 Rigging, of which the following is a specification, this application being a division of an application filed March 13, 1907, by said WILLIAM P. BETTENDORF, Serial No. 362,176.

This invention has relation to that type of 15 draft rigging for railway cars, especially freight cars, in which the draft rigging is inclosed between a pair of separated sills or beams and the shank of the coupler is slid- 20 ingly supported therebetween; and the ob- ject of this invention is to provide improved 25 means for supporting the shank of the coupler, to the end that the danger of the coupler being jarred loose and allowed to fall from between the draft sills shall be greatly reduced, as more fully hereinafter set forth.

In the drawings,—

Figure 1 is a perspective view showing the draft members separated from each other and the center sills of the car; 30 Fig. 2 is a horizontal sectional view on the line 2—2 of Fig. 3, showing the parts as they appear when assembled; and

Fig. 3 is a vertical sectional view on the line 3—3 of Fig. 2.

Referring to the drawings annexed by reference characters, *a*, *a* designate the main side members or bars of the draft rigging frame, which are preferably of cast steel and which are adapted to be attached in any 40 suitable manner at their rear ends to the center sill structure *b*. These draft sills are separated a sufficient distance and are suitably shaped to receive the usual spring draft gear. The forward ends of these draft sills 45 preferably extend through an opening in the end sill *c* of the car underframe and are rigidly connected together by a face plate *d*, this plate being riveted rigidly to the front flat end faces of the draft sills. At the forward ends of each of the draft sills is an inwardly extending lug or projection *e*, the 50 projections on the two members abutting together at the vertical center of the rigging

and thus serving to assist in spacing the front end of the draft structure. 55

The forward end of the draft structure is further braced by means of a horizontal bar *f* which is rigidly secured between the lower forward corners of the draft members by means of a horizontal bolt *g* extending 60 through the draft members and longitudinally through the bar. The ends of the bar *f* abut rigidly against the inner faces of the draft beams and the upper face of the bar at its ends abuts against downwardly facing 65 shoulders *h* formed on the respective draft members. This bar *h* not only serves to brace the forward end of the draft structure, but also serves as a support or carrier for the shank of the slideable coupler, and its 70 advantage as such is that it not only may be easily and quickly replaced when worn or broken, but also that by reason of being supported on a horizontal bolt or rod its detachment from the draft structure is 75 prevented or rendered extremely unlikely. Heretofore the supports for the coupler shanks have been fastened to the draft beams by means of vertical bolts, so that when the nuts on the bolts work loose or the bolt is 80 broken, the support will fall from between the draft sills and permit the coupler to sag or fall out of the draft structure. With this improved coupler shank support, it will be seen that even though the nut on the bolt 85 works off the bolt, it will be extremely unlikely to drop the coupler shank for a considerable time, that is, before the dangerous condition is discovered.

It will be observed that the striking plate 90 *d* (which directly or indirectly receives the bumping impact) extends across the upper edges of the ends of the sills, thereby forming the coupler-shank opening between this striking plate and the supporting-bar *f*. 95 It will be observed also that the supporting-bar *f* is non-rotatable, being prevented from rotation by the rigid engagement of the ends with the sills and also by engagement against downwardly-facing shoulders *h*. 100 Constructed in this manner, it will be seen that the forward end of the draft structure is very simple in construction and yet very rigid and durable.

What is claimed as new is:

In a draft rigging for railway cars, a pair

105

of separated draft sills adapted to receive the draft rigging between them and provided with downwardly-facing shoulders on their inner faces near their lower front corners, a striking plate extending across the front ends of the draft sills, a coupler-shank supporting-bar having its ends rigidly abutting the inner faces of the sills and in en-

gagement with the aforesaid downwardly-facing shoulders, and a horizontal bolt extending through the sills and longitudinally through said supporting-bar. ¹⁰

In testimony whereof I hereunto affix my signature.

JOSEPH W. BETTENDORF.
